UNITED STATES PATENT OFFICE.

JOHN B. MUNSON, OF PHILLIPSBURG, NEW JERSEY.

DESIGN FOR A FLAG.

46,539.

Specification for Design.

Patented Oct. 13, 1914.

Application filed August 10, 1914. Serial No. 856,144. Term of patent 7 years.

To all whom it may concern:

Be it known that I, JOHN B. MUNSON, a citizen of the United States, residing at Phillipsburg, in the county of Warren and State of New Jersey, have invented a new, original, and ornamental Design for Flags, of which the following is a specification, reference being had to the accompanying drawing, forming part thereof.

The figure is a plan view of a flag, showing my new design.

Referring more particularly to the drawing it will be seen that my improved flag

design consists of the alternately disposed and longitudinally extending red and white bars provided with an annular area of blue disposed near one end thereof, the latter having a yellow star provided with a centrally arranged cross as shown.

I claim:

The ornamental design for a flag, as shown and described.

JOHN B. MUNSON.
